UNITED STATES PATENT OFFICE.

CHARLES ZABEL, OF CORAOPOLIS, PENNSYLVANIA, ASSIGNOR TO BRUNO ZABEL, OF PITTSBURGH, PENNSYLVANIA.

MECHANICAL TOY.

Application filed January 24, 1923. Serial No. 614,568.

To all whom it may concern:

Be it known that I, CHARLES ZABEL, a citizen of the United States, residing at Coraopolis, in the county of Allegheny and 5 State of Pennsylvania, have invented certain new and useful Improvements in Mechanical Toys, of which the following is a specification.

This invention is for a mechanical toy of 10 the type in which a miniature vehicle is raised from a lower track to an elevated track, from which it gravitates back to the lower one, mechanical means being provided for transferring the vehicle from the lower 15 to the upper track.

The objects of the present invention are to provide a pleasing toy of simple mechanical construction, which is compact and may be cheaply manufactured, the primary object of 20 the invention being to provide a more simple mechanism for transferring the vehicle from one track to the other, the necessity for intermittently driving the operating mechanism in toys of this kind being eliminated 25 in the present case.

My invention may be readily understood by referring to the accompanying drawings, in which:

Fig. 1 is a side view of the assembled toy, 30 showing the parts in one position;

Fig. 2 is a side view of the assembled toy, the spring motor and certain parts of the frame being broken away, the parts being 35 in a different position;

Fig. 3 is a section on line III—III of Fig. 2;

Fig. 4 is a perspective view of a detail of the upper track;

Fig. 5 is a perspective view showing a 40 separable joint in the lower track;

Fig. 6 is a side view of the driving means and supporting structure on a large scale, parts of the motor support being broken away;

Fig. 7 is a horizontal section on line 45 VII—VII of Fig. 6; and

Fig. 8 is a modification of the driving means showing how an electric motor may be substituted for the spring motor.

In the drawings, 5 designates an integral base which is preferably formed of sheet metal having downwardly turned edges. Secured to the base are two transverse strips 6 and 6' having upturned ends 7 and 7' respectively.

Secured by rivets or other suitable means to the upturned ends 7 and 7' at one end of strips 6 and 6' is an arch 8, and similarly connected to the other upturned ends of the two strips is a second arch 8^a. The arches 8 and 8^a are similarly constructed, preferably from thin sheet metal which is channel shaped in cross section, the channels being turned outwardly. They are of the same dimensions and are parallel to each other. 60

Supported in the two arches is a transverse shaft 9. Pivoted on this shaft by means of ears on the under side thereof, is section 10 of the lower track. By reference to the drawings, it may be seen that the pivotal support for the track section 10 is adjacent one end thereof. The same end is provided with a slot 10^a into which tongue 10^b of the other section 10' of the lower track fits in such manner as to form a rigid detachable joint. The entire lower track, therefore, comprises two sections 10 and 10', joined together and pivotally supported about midway between its ends. The two sections are joined at an angle, so that one 70 end of the lower track will always be considerably higher than the middle. This lower track is made with the removable section 10' in order to minimize the overall length required for packing the toy for 75 shipment.

The track is preferably made of sheet metal, bent to the cross section shown in Fig. 3 to provide parallel grooves 10^c. At each end of the lower track is a vertical post 90 11 forming an abutment or stop to prevent the miniature vehicle or other object, hereinafter described, from rolling off the track.

At one side of the lower track on section 10, and carried thereby, is a perpendicular 95 plate 12 having a cam slot 13 therein. This slot is of a peculiar shape, having a narrow neck portion which opens into a cut-away area of increasing width.

Mounted on the side frame or arch 8 is a 100 driving gear comprising a gear wheel 14, a gear wheel 15 driven thereby, and a speed governor 16 driven by wheel 15. Wheel 14 may be driven by a spring motor 17, as shown in Figs. 6 and 7, or by a small electric 105 motor designated 17' in Fig. 8.

The pinion or gear wheel 14 has a pin 18 projecting therefrom, which engages in the slot 13 of plate 12. Upon rotation of the pinion, the lower track, through slot 13 and 110

pin 18, is caused to rock on shaft 9, so that first one end is high and then the other, in the manner of a seesaw.

The speed governor wheel 16 is made of a soft rubber disk having weights 16^a near its periphery. At 19 is a leaf spring adapted to be moved toward or away from the disk 16 by screw 20. When disk 16 is revolved at high speed, the weights cause it to increase in diameter, and the leaf spring 19 acts as a brake on the periphery of wheel 16. By suitable adjustment of screw 20, the speed at which the lower track is rocked can be controlled.

Extending across the two frames 8 and 8', is an upper shaft 21 which provides a support for the upper track. The upper track 22 is similar in construction to the lower track. At a point substantially midway between its ends is secured a cross member 23 of the shape shown in Fig. 4, having one end turned downwardly at 24, the end 24 being slotted to fit over shaft 21. The other end of member 23 is turned downwardly and slotted at 25 to also fit over shaft 21. Extending forwardly from the turned down slotted portion, is an offset portion 26 having a depending arm 27 and a lateral projection 28.

As thus constructed, a pivotal support for the upper track is provided, and the upper track may be readily removed and put back in place. The upper track is so balanced that end *a* is heavier than end *b*, and when in place, projection 28 on arm 27 engaging under arch 8' limits the distance which the upper track may rock in one direction, Fig. 1 showing the end *a* in its lowest possible position.

Any suitable means may be used to roll back and forth on the tracks, as hereinafter described, but I prefer to use a wheeled vehicle. As shown in the drawing, the vehicle A preferably comprises a body 30 having depending side edges which provide bearings for transverse shafts 31 and 32 on which are wheels 32^a. Shaft 32 is provided with a crank which reciprocates a rod 33. Rod 33 is connected to the lower end of a vertical post 34 mounted to rock on the body. Secured to the body are legs 35 of miniature imitation persons in sitting posture, 36 indicating the trunks of the figures, which have a pivoted connection with the legs. Pivottally connected with the bodies are arms 37 which connect with the top of post 34. When shaft 32 revolves by movement of the car, rod 33 reciprocates, rocking post 34, which reciprocates arms 37 and rocks bodies 36, giving the appearance of two figures driving a hand car.

The operation of the toy may now be described. Assuming the car A to be in the position shown in Fig. 1, the motor rotates pinion 14 in such direction as to cause pin

18 to rock the lower track to raise end 10. As end 10 lifts, it will engage end *a* of upper track 22, also rocking the upper track to the dotted line position of Fig. 2. Car A will then roll down track 22, causing end *b* to tilt down to the lower track section 10', which is the full line position of the upper track in Fig. 2.

When the car reaches the position shown in Fig. 2, pin 18 has reached a position where the lower track begins to rock in the opposite direction. When section 10' has been sufficiently lowered, upper track 22 will assume the position shown in Fig. 1 by reason of the end *a* being the heavier. After the lower track has been rocked sufficiently to incline section 10', car A will gravitate back to the position shown in Fig. 1, and the cycle of operation will be repeated.

The fact that the pinion 14 is continuously driven readily enables an electric motor to be utilized in a very simple form of toy, whereas in toys of this nature as hereinbefore made, the operating mechanism had to run intermittently, complicating considerably the use of the toy with a continuously driven motor.

As constructed, the toy may be partially taken apart for packing and shipping, and readily assembled. The parts are so located with relation to the base that when packed, no part projects any substantial distance beyond the base, and are therefore protected.

Various modifications and changes may be made in the construction shown, however, within the contemplation of my invention and within the scope of the appended claims.

I claim as my invention:

1. A toy comprising an upper track, a lower track of greater length than the upper track, means for rocking the lower track to alternately elevate opposite ends, and an object adapted to travel in the tracks by gravity, the rocking motion of said lower track in one direction serving to elevate said object to the upper track from whence it rolls to the lower track, the rocking motion of the lower track in the other direction serving to return the object along the lower track to position to be again elevated.

2. A toy comprising tilting upper and lower tracks, means for positively tilting the lower track to alternately elevate its ends, an object adapted to travel on said tracks, said tracks being so arranged that the object may initially be raised from one end of the lower track to the upper track from whence it gravitates to the other end of the lower track and upon rocking of the lower track returned along the lower track to its initial position.

3. A toy comprising a tilting lower track, said lower track being pivotally supported between its ends and so shaped as to have

- two portions which converge adjacent the pivotal support, means for rocking the lower track in a seesaw fashion, an upper track pivotally supported above the lower track and arranged to normally remain in one position, said upper track being so positioned over the lower track as to contact with and be tilted by one part of the lower track upon the upward movement thereof, and an object adapted to roll in said tracks by gravity. 5
4. A toy comprising a pivotally supported lower track arranged to rock in a seesaw fashion, an upper track of less length than the lower track similarly mounted and spaced above the lower track, one end of the lower track being arranged to contact with and move higher than the upper track upon being rocked upwardly, and a rolling object adapted to travel in said tracks by gravity and to be transferred from one track to the other by the rocking motion thereof. 10
5. A toy comprising a pivotally supported lower track arranged to rock in a seesaw fashion, an upper track of less length than the lower track similarly mounted and spaced above the lower track, one end of the lower track being arranged to contact with and move higher than the upper track upon being rocked upwardly, means for rocking the lower track, and a rolling object adapted to travel in said tracks by gravity and to be transferred from one track to the other by the rocking motion thereof. 15
6. A toy comprising a pivotally supported lower track arranged to rock in a seesaw fashion, an upper track of less length than the lower track similarly mounted and spaced above the lower track, one end of the lower track being arranged to contact with and move higher than the upper track upon being rocked upwardly, and power driven means for continuously rocking the lower track during the operation of the toy, and a rolling object adapted to travel in said tracks by gravity and to be transferred from one track to the other by the rocking motion thereof. 20
7. A toy comprising an upper track, a lower track pivotally supported therebeneath and of greater length than the upper track, means for rocking said lower track in a seesaw fashion, and a traveling object arranged to roll in said track by gravity, the arrangement being such that the seesaw motion of the lower track elevates said object to one end of the upper track along which it moves back to the other end of the lower track, whence it returns to a position to be again elevated. 25
8. A toy comprising an upper track, a lower track having a bend therein pivotally supported therebeneath and of greater length than the upper track, means for rock- 30
- ing said lower track in a seesaw fashion, and a traveling object arranged to roll in said track by gravity, the arrangement being such that the seesaw motion of the lower track elevates said object to one end of the upper track along which it moves back to the other end of the lower track, whence it returns to a position to be again elevated. 70
9. A toy comprising an upper track, a lower track pivotally supported therebeneath, a cam plate having a cam slot therein carried by the lower track, an eccentric pin engaging in said slot, means for driving the pin, said pin and slot being arranged to rock said lower track in a seesaw fashion, and an object adapted to roll by gravity along said upper and lower tracks. 75
10. A toy comprising an upper track pivotally supported between its ends, one end of said track being heavier than the other, whereby it is urged by gravity to one position, means for limiting the rocking movement of the upper track in the direction in which it is urged by gravity, a second track longer than the upper track and spaced below it, said lower track also being pivotally supported, means for rocking said lower track in a seesaw fashion, and an object arranged to roll along said tracks. 80
11. A toy comprising a supporting structure, a removable upper track pivotally supported thereon, a lower track spaced below the upper track and of greater length than the upper track, said lower track comprising a pivotally supported section and a removable section connected therewith, said removable section joining the pivoted section at an angle thereto, means for rocking the lower track, and an object arranged to roll on said tracks. 85
12. A toy comprising a base, a pair of spaced apart substantially parallel arches on said supporting member, an upper shaft connecting the two arches, an upper track pivoted thereon, so that it is free to rock, means for limiting the rocking movement in one direction, a lower shaft connecting the arches, a lower track pivotally supported on the lower shaft and of greater length than the upper shaft, operating means supported on one of said arches, means on the lower track cooperating with said operating means, said operating means being arranged to rock the pivoted lower track, and an object arranged to roll from one track on to the other with the rocking movement thereof. 90
13. The combination with a toy having tiltable tracks, of a car adapted to roll in said tracks by gravity, said car comprising a platform, axles supported thereon, wheels on said axles, one of the axles being rotated by the wheels and having a crank formed therein, a post connected with said crank and oscillated by the rotation thereof, 105
- 110
- 115
- 120
- 125
- 130

- and a miniature figure connected with said post through its arms and rocked by the oscillations thereof, said carriage simulating a hand car which is driven by the figure.
- 5 14. A toy comprising a supporting structure, a lower track, an upper track pivotally mounted on the supporting frame, and means including an arm connected with the upper track section adapted to contact with 10 a stationary part of said frame to limit the rocking movement of the frame.
15. A toy comprising a supporting structure, a lower track section, an upper track section, said upper track section having a cross member secured thereto having downwardly bent portions in which are notches, a shaft comprising part of the supporting structure, said turned-down notched portions of the strip resting on said shaft and 20 providing a pivotal support for said shaft over the lower track and enabling said upper track section to be readily removed, and means on the cross member for engagement with the supporting structure to limit the 25 rocking movement of said upper track section.
16. A toy having upper and lower tracks, the lower track being longer than the upper track in order that an object adapted to roll 30 on said tracks may be received from one end of the upper track to the lower track and be returned to the opposite end of said upper track and formed in separable sec-
- tions, both tracks being channel like in cross section, one section of the lower track having a transverse slot therein spaced back from the end thereof, the other section of the lower track having a tongue therein depressed below the bottom of the channel and extending into the slot in the other track section, the end portion of the tongue section being received in and resting on the channeled end of the slotted section. 35
17. A toy having upper and lower tracks, the lower track being longer than the upper track in order that an object adapted to roll on said tracks may be received from one end of the upper track to the lower track and be returned to the opposite end of said upper track and formed in separable sections, both tracks being channel like in cross section, one section of the lower track having a transverse slot therein spaced back from the end thereof, the other section of the lower track having a tongue therein depressed below the bottom of the channel and extending into the slot in the other track section, the end portion of the tongue section being received in and resting on the channeled end of the slotted section, the 40 sides of the channels of the two members contacting to assist in holding said sections in line with each other. 45
- 50 In testimony whereof I affix my signature.
